Attorney

UNITED STATES PATENT OFFICE.

JOHN KUNZELMANN, OF BALTIMORE, MARYLAND.

WINDOW-SASH.

1,195,690.

Specification of Letters Patent. Patented Aug. 22, 1916.

Application filed July 1, 1915. Serial No. 37,442.

To all whom it may concern:

Be it known that I, JOHN KUNZELMANN, a subject of the Emperor of Germany, residing at Baltimore city, State of Maryland, have invented certain new and useful Improvements in Window-Sashes, of which the following is a specification.

This invention relates to window sashes which are constructed of sheet metal, and its object is to provide a novel and improved sash of this kind which is so constructed and assembled that it makes a weathertight joint with the window frame, and is also held against rattling.

The invention also has for its object to provide a sash which slides freely in the guide channels of the window frame jambs.

The objects stated hereinabove are attained by means of a combination and arrangement of parts to be hereinafter described and claimed, and in order that the same may be better understood, reference is had to the accompanying drawing, in which—

Figure 1 is a side elevation of one side of the sash, with parts in section; Fig. 2 is a horizontal section through one side of the sash and the window frame, and Fig. 3 is an enlarged horizontal section of one of the sash stiles and the portion of the window frame engaged thereby.

Referring specifically to the drawing, 5 denotes a hollow sheet metal jamb of a window frame, the same having the usual parallel vertical guide channels 6 for the window sashes 7, the latter being slidable in the channels. The stiles and bars of the sashes are also hollow and made of sheet metal. Each sash stile comprises spaced inner and outer face portions 8 and 9, respectively, and an edge portion 10. The pane 11 is mounted in the sash frame in any suitable manner. The edge portion 10 of the stile is a sheet metal strip which is located between the face portions 8 and 9, a short distance inward of the outer vertical edges thereof. The strip has outstanding diverging flanges 12 at its opposite vertical edges, said flanges extending into the channel 6, and having their extremities bent back in the form of hooks 13 over the outer faces of the vertical edge portions of the parts 8 and 9 which are located in the channel, whereby the strip is made fast to said parts 8 and 9. That portion of the stile which seats in the channel is reduced in width by

bending the edge portion of the parts 8 and 9 inward toward each other, as indicated at 14, and said bends terminate in outward or diverging bends 15 to receive the bends 13. 60 The bends 14 start at the outer corners 16 of the channel 6, and form rounded shoulders on the parts 8 and 9 which fit and bear against said corners.

The distance between the corners 16 of 65 the channel 6 is slightly less than the distance between the outer faces of the parts 8 and 9, so that when the sash is mounted in place, said parts must be pressed slightly together to engage the channel corners, and 70 as they are resilient they fit snugly against the channel corners and yieldingly engage the same, thereby making a weathertight joint, and also preventing rattling of the sash. The sash however is free to slide as 75 the parts 8 and 9 do not press the channel corners with sufficient force to cause binding owing to the slight engagement of the rounded corners. The flanges 12 are joined to the body of the strip 10 by curved bends 80 17 one at each edge which are spaced a short distance from the inner surface of the parts 8 and 9, to allow the latter to yieldingly engage the channel corners as described. These bends resiliently connect the flanges 85 to the body of the strip, and the flanges are therefore free to yield with the parts 8 and 9 to which they are connected and their resiliency is reinforced by the resilient bends 90 of the edge strip.

To facilitate sliding of the sash, the edge strip 10 carries rollers 18 mounted in the channel 6 to engage the rear face thereof. A pair of rollers is located at the top, and another pair at the bottom of the sash. Each 95 pair of rollers is carried by a block 19 secured to the outer face of the strip 10 by bolts 20 or other suitable fasteners. The strip 10 is recessed at 21 to accommodate the rollers, and the latter and the block 19 100 are located between the flanges 12. The members of the respective pairs of rollers are laterally spaced and form a wide bearing for the sash, thereby preventing binding of the same in the channel 6. As the sash 105 is in contact with the jamb only at the corners of the channel, friction is reduced to a minimum, and the sash slides free and easy.

The structure provides a sheet metal sash without complicated parts liable to get out 110 of order, and a sash which can be easily and cheaply manufactured. The sash is also

weathertight, and it can be easily raised and lowered.

I claim:

1. In combination with the jambs of a window frame having guide channels, a sash slidably mounted in said channels, the stiles of said sash comprising spaced resilient sheet metal inner and outer face portions which have their outer edges bent toward each other to provide rounded shoulders on each side of the sash and which are spaced apart slightly wider than the width of said guide-channels to yieldingly engage the outer corners thereof and leaving said outer edges free from engagement with the sides of the guide-channels, and means on said sash for positioning and retaining said rounded shoulders at the outer corners of the guide-channels.

2. In combination with the jambs of a window frame having sash guide channels, a sash slidably mounted in said channels, the stiles of said sash comprising spaced sheet metal inner and outer face portions which have their outer edges bent toward each other to provide rounded shoulders which yieldingly engage the outer corners of said guide channels and leaving said outer edges free from engagement with the sides of said guide channels, and an edge strip located between said inner and outer face portions which tends to force the sides of the sash stiles outwardly and provided with resilient outstanding flanges which are attached to the rear vertical edges of the bent-in outer edges of said face portions.

In testimony whereof I affix my signature.
JOHN KUNZELMANN.
